Primary Examiner — Patricia A Palasik(74) *Attorney, Agent, or Firm* — Sutdebaker & Brackett
PC(57) **CLAIM**

The ornamental design for a manipulator for robot, as shown and described.

DESCRIPTION

FIG. 1 is a front perspective view of the front, right, and top sides of a manipulator for robot showing a first embodiment of our new design;

FIG. 2 is a rear perspective view of the rear, left, and bottom sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a part 9; and,

FIG. 10 is an enlarged view of a part 10.

The broken lines in the drawings represent portions of the manipulator for robot and form no part of the claimed design.

1 Claim, 10 Drawing Sheets---
